DISPENSING CONTAINER

Filed Oct. 18, 1938

Fig. 1.

Aug. 1910 2

A diagram of a cell with a nucleus and organelles.

The diagram illustrates a cross-section of a plant stem with various internal structures labeled 1 through 12. The labels indicate the following parts from the outside in:

- 1: Epidermis
- 2: Subepidermal layer
- 3: Ground tissue
- 4: Vascular tissue
- 5: Cambium
- 6: Pith
- 7: Endodermis
- 8: Pericycle
- 9: Vascular tissue (inner)
- 10: Cambium
- 11: Ground tissue
- 12: Epidermis

DISPENSING CONTAINER

Owen F. Steward, North Woodbury, N. J.

Application October 18, 1938, Serial No. 235,647

1 Claim. (Cl. 65—57)

My invention relates to improvements in dispensing containers for use more particularly in dispensing salt, although, as will presently appear, it may be used with equal advantage in dispensing other granular substances, also tooth-paste and liquid soap.

The principal object of the invention is to provide an efficient, inexpensive container of the class above indicated equipped with easily operative manipulative means for positively breaking up caked contents in the container and feeding the same therefrom.

My invention also comprehends other and subordinate objects, all of which, together with the precise nature of my improvement will be readily understood when the succeeding description and claim are read with reference to the drawing accompanying and forming part of this specification.

20 In said drawing:

Figure 1 is a view in side elevation of a dispensing container forming a preferred embodiment of my invention.

Figure 2 is a view in vertical longitudinal section.

Figure 3 is a view in top plan.

Figure 4 is a view in transverse section taken on the line 4—4 of Figure 2 looking in the direction indicated by the arrows.

30 Figure 5 is a similar view taken on the line 5—5 of Figure 2 looking in the direction indicated by the arrows.

Referring to the drawing by numerals, and first to Figures 1 to 5 thereof, the container of my invention in the preferred embodiment thereof comprises a preferably cylindrical receptacle 1 of any suitable material closed at its bottom, as at 2, and having a reduced externally threaded neck 3. Threaded onto the neck 3 is a cap-like 35 spider 4 comprising a central hub 5 and provided in the top thereof with a series of large openings 6 grouped around said spider. Surmounting the spider 4 is a foraminous spray cap 7 having an internal edge flange 8 fitting loosely 40 into a circular groove 9 provided in the side of the spider 4. A headed screw 10 extends through the cap 7 and hub 5 into a socket 11 provided on one end of a helical blade 12 preferably ter-

minating short of the bottom 2 of the receptacle 1. The screw 10 has a squared part 13 fitting into a correspondingly shaped opening 14 in the cap 7 whereby said cap is keyed to said screw. The screw 10 is threaded, as shown in dotted 5 lines, tightly into the socket 11 and the blade 12 clears the spider 4 and the inner periphery of the receptacle 1.

As will now be seen, the cap 7 is rotatably mounted on the spider 4 so that under rotation 10 of said cap in the proper direction the blade 12 will be rotated through the medium of the screw 10 to break up the contents of the container 1 and feed the same out of the openings 6 and also out of the cap 7.

In the described embodiment of the invention, it will be noted that the cap 7 will be prevented from becoming clogged by rotation over the spider 4. Also the end of the blade 12 adjacent to the spider 4 is likewise formed straight to 20 keep the opening 6 clear.

My invention will, it is believed, be readily understood from the foregoing without further explanation.

Manifestly, the invention as described, is susceptible of modification in other respects than as disclosed herein and right is herein reserved to such other modifications as fall within the scope of the subjoined claim.

What I claim is:

A dispensing container comprising a receptacle having a cylindrical externally threaded neck, a cap-like spider having a hub part and circular discharge apertures therein grouped about said part and a circular edge flange threaded onto 35 said neck and provided with a circumferential groove therein, a circular foraminous spray cap fitting flush over said spider and having a right-angled continuous edge flange fitting into said groove and permanently locking said cap to said 40 spider for rotation thereon, a helical blade in said receptacle, and a stud having its opposite ends fixed in said cap and one end of said blade, respectively, and extending loosely through said hub whereby said blade is rotatable by 45 said cap.

OWEN F. STEWARD.
